TWO-PIECE WAISTLINE BELT FOR
UNIFORMS AND OTHER GARMENTS

Abraham Friedman, New York, N. Y.

Application February 11, 1942, Serial No. 430,334

6 Claims. (Cl. 2—74)

This invention relates to new and useful improvements in a two piece waistline belt for uniforms and other garments.

More specifically, the invention proposes the construction of a two piece waistline belt adapted to be used in conjunction with an article of wearing apparel comprising a bodice portion and a skirt portion arranged in a manner to be connected together by means of said waistline belt to cause the skirt to flare outwards and downwards from the bodice portion.

More specifically, it is proposed to characterize the waistline belt by a straight top belt section of cylindrical form which has its bottom edge stitched to the concave side of an arcuately shaped bottom belt section in a manner to cause the bottom belt section of the waistline belt to flare outwards.

Still further it is proposed to attach the bottom edge of the bodice portion to the free top edge of the straight top belt section and to attach the top edge of the skirt portion to the outwardly flared bottom edge of the bottom belt section in a manner to utilize the outwardly flared formation of the bottom section of the belt to assist in causing the skirt portion to drape in the desired outwardly flared formation.

A further object of the invention proposes to provide the arcuately shaped bottom belt section with a layer of lining material extending along the back face thereof and which is provided with a plurality of superimposed longitudinally extending tubular portions through which a draw string is adapted to be selectively extended in a manner to draw in the bottom portion of the bottom belt section and control the outward flaring of this section.

For further comprehension of this invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a front view of a garment having a two piece waistline belt constructed in accordance with this invention.

Fig. 2 is a rear elevational view of Fig. 1.

Fig. 3 is a developed view of the waist portion of the garment.

Fig. 4 is a perspective view of the top belt section.

Fig. 5 is a perspective view of the bottom belt section.

Fig. 6 is an enlarged vertical sectional view taken substantially on the line 6—6 of Fig. 2.

Fig. 7 is a view similar to Fig. 6 but illustrating a modification of the invention.

Fig. 8 is a similar view to Fig. 5, but illustrating another modification of the invention.

The two piece waistline belt for uniforms and other garments is adapted to be used in connection with an article of ladies' wearing apparel comprising a garment 10 having a bodice portion 11 and a skirt portion 12. The garment 10 may be constructed of any desired cloth material and the bodice portion 11 is provided with a conventional collar 12 and a sleeve 13.

A two piece waistline belt 14 is provided for connecting the bottom edge of the bodice portion 11 to the top edge of the skirt portion 12 at a position coinciding with the waist of the wearer. This two piece waistline belt 14 comprises a straight top belt section 15 of substantially cylindrical shape and which has its top edge attached to the bottom edge of the bodice portion 11 by means of a line of stitches 16. An arcuately shaped bottom belt section 17 has its top concaved side attached to the bottom edge of the top belt section 15 by means of a line of stitches 18. The convex bottom edge of the arcuately shaped bottom belt section 17 is in turn attached to the top edge of the skirt portion 12 by means of a line of stitches 19.

The adjacent edges of the belt sections 15 and 17 are provided with aligned notches 20 spaced to conform with the seams of the skirt, along the length of the belt sections in a manner to act as guides in attaching the adjacent edges of these belt sections. It will be noted that when the concave side of the bottom belt section 17 is attached to the straight bottom edge of the belt section 15 the arcuate formation will cause the bottom belt section 17 to assume an outwardly flared position with relation to the top belt section. When the top edge of the skirt portion 12 is then attached to the bottom edge of the outwardly flared bottom belt section 17 the normal outward flare of the belt section 17 will assist in draping the skirt 12 in the desired outwardly flared formation.

In the modification of the invention shown in Fig. 7 the arcuately shaped bottom belt section 17 is provided with a lining layer of cloth material 21 which is secured in position by the lines of stitches 18 and 19 which secure the top and bottom edges of the bottom belt sections 17 to the adjacent edges of the top belt section 15 and the top edge of the skirt portion 12.

The layer of lining material 21 is provided with a plurality of longitudinally extended tubular portions 22 arranged at several different vertical positions along the height of the lining material 21. These tubular portions are formed by drawing in areas of the lining layer and securing these drawn in areas in position by means of lines of stitches 23. A draw string 24 is adapted to be removably engaged through one of the

tubular portions 22 and have its ends extended through an opening 25 formed in the tubular portions 22 in a manner to be pulled and tied together for drawing in the lining layer 21 and in turn drawing in the bottom belt sections 17 to control the angular flaring of the bottom belt section.

The lining layer 21 is securely attached to the bottom belt section 17 by means of lines of stitches 26 engaged through these portions and which run parallel to each other at positions substantially intermediate the tubular portions 22. In other respects this form of the invention is similar to the previous form and like parts are identified by like reference numerals.

In Fig. 8, the bottom belt section 17' is made of straight edges and is provided with a plurality of arcuate folds or pleats 17^b to form substantially arcuate end portions 17^a. The substantially arcuate belt section 17' may also be used in place of the arcuate belt section 17, in conjunction with the straight top belt section 15 to cause the skirt to flare outwardly and to make the skirt cling to the body of the wearer.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A two piece waistline belt, comprising a straight top belt section of cylindrical form for attachment to the bottom edge of the bodice portion of a garment, and a substantially arcuate bottom belt section having its concaved side stitched to the free bottom edge of said top section and its convexed side flared downwards and outwards for attachment to the top edge of the skirt portion of said garment which has its top portion flared downwards and outwards.

2. A two piece waistline belt, comprising a straight top belt section of cylindrical form for attachment to the bottom edge of the bodice portion of a garment, and a substantially arcuate bottom belt section having its concaved side stitched to the free bottom edge of said top section and its convexed side flared downwards and outwards for attachment to the top edge of the skirt portion of said garment which has its top portion flared downwards and outwards, and means for controlling the downward and outward flaring of said bottom belt section to correspondingly control the flaring of the skirt portion when attached thereto.

3. A two piece waistline belt, comprising a straight top belt section of cylindrical form for attachment to the bottom edge of the bodice portion of a garment, and a substantially arcuate bottom belt section having its concaved side stitched to the free bottom edge of said top section and its convexed side flared downwards and outwards for attachment to the top edge of the skirt portion of said garment which has its top portion flared downwards and outwards, and means for controlling the downward and outward flaring of said bottom belt section to correspondingly control the flaring of the skirt portion when attached thereto, comprising lining material extended along the back face of said bottom belt section, vertically spaced horizontal tubular

passages formed in said lining material, and a draw string removably engaged through one of said tubular passages.

4. A two piece waistline belt, comprising a straight top belt section of cylindrical form for attachment to the bottom edge of the bodice portion of a garment, and a substantially arcuate bottom belt section having its concaved side stitched to the free bottom edge of said top section and its convexed side flared downwards and outwards for attachment to the top edge of the skirt portion of said garment which has its top portion flared downwards and outwards, and means for controlling the downward and outward flaring of said bottom belt section to correspondingly control the flaring of the skirt portion when attached thereto, comprising lining material extended along the back face of said bottom belt section, vertically spaced horizontal tubular passages formed in said lining material, and a draw string removably engaged through one of said tubular passages, said tubular passages being formed by drawing in vertically spaced areas of said lining and securing said drawn in areas in position by means of lines of stitches.

5. A two piece waistline belt, comprising a straight top belt section of cylindrical form for attachment to the bottom edge of the bodice portion of a garment, and a substantially arcuate bottom belt section having its concaved side stitched to the free bottom edge of said top section and its convexed side flared downwards and outwards for attachment to the top edge of the skirt portion of said garment which has its top portion flared downwards and outwards, and means for controlling the downward and outward flaring of said bottom belt section to correspondingly control the flaring of the skirt portion when attached thereto, comprising lining material extended along the back face of said bottom belt section, vertically spaced horizontal tubular passages formed in said lining material, and a draw string removably engaged through one of said tubular passages, said lining layer being secured to said bottom belt section by means of horizontal lines of stitches disposed between said tubular portions.

6. A two piece waistline belt, comprising a straight top belt section of cylindrical form for attachment to the bottom edge of the bodice portion of a garment, and a substantially arcuate bottom belt section having its concaved side stitched to the free bottom edge of said top section and its convexed side flared downwards and outwards for attachment to the top edge of the skirt portion of said garment which has its top portion flared downwards and outwards, and means for controlling the downward and outward flaring of said bottom belt section to correspondingly control the flaring of the skirt portion when attached thereto, comprising lining material extended along the back face of said bottom belt section, vertically spaced horizontal tubular passages formed in said lining material, and a draw string removably engaged through one of said tubular passages, said tubular passages being formed with openings at one side thereof and said string being adapted to have its ends projected from the opening in the passages with which it is engaged in a manner to be pulled and tied together for drawing in and holding said bottom belt section drawn in.

ABRAHAM FRIEDMAN.
